DESIGN FOR A HANDBAG

Ludwig Kaphan, Brooklyn, N. Y.

Application December 2, 1944, Serial No. 116,668

Term of patent 14 years

(Cl. D67—3)

To all whom it may concern:

Be it known that I, Ludwig Kaphan, a citizen of the United States, residing at Brooklyn, county of Kings, and State of New York, have invented a new, original, and ornamental Design for Handbag, of which the following is a specification, reference being had to the accompanying drawing, forming part thereof, in which:

Fig. 1 is a side elevational view of a handbag showing my new design;

Fig. 2 is an end elevational view thereof;

Fig. 3 is a bottom plan view thereof; and

Fig. 4 is a top plan view thereof.

The elements are shown only on part of the bag in Figs. 1 and 3 for convenience of illustration. It is to be understood that these elements continue uniformly throughout the broken lines in precisely the form and manner as shown where they terminate on the sides and also on the handle of the bag.

I claim:

The ornamental design for a handbag, as shown and described.

LUDWIG KAPHAN.
